UNITED STATES PATENT OFFICE

143,289

DESIGN FOR A CLOSURE CAP FOR A TWO-COMPARTMENT CONTAINER

William D. Elsas, Kew Gardens, Paul Lowengardt, Forest Hills, and Alexander Scheftel, New York, N. Y.

Application April 2, 1945, Serial No. 118,820

Term of patent 3½ years

(Cl. D58—26)

To all whom it may concern:

Be it known that we, William D. Elsas, a citizen of the United States, residing in Kew Gardens, county of Queens and State of New York, and Paul Lowengardt, a citizen of the United States, residing in Forest Hills, county of Queens, State of New York and Alexander Scheftel, a citizen of the United States, residing in the city, county, and State of New York, have invented a new, original, and ornamental Design for a Closure Cap for a Two-Compartment Container, of which the following is a specification, reference being had to the accompanying drawing, forming part thereof.

Fig. 1 is a perspective view of a closure cap for a two-compartment container showing our new design;

Fig. 2 is a top view thereof;

Fig. 3 is a side elevational view;

We claim:

The ornamental design for a closure cap for a two-compartment container, as shown.

WILLIAM D. ELSAS.

PAUL LOWENGARDT.

ALEXANDER SCHEFTEL.
